UNITED STATES PATENT OFFICE.

THOMAS H. LINDLEY, OF CEDAR RAPIDS, IOWA, AND HERMAN SCHREIER, OF SHEBOYGAN, WISCONSIN.

ROTARY ENGINE.

1,220,244.

Specification of Letters Patent.

Patented Mar. 27, 1917.

Application filed August 5, 1916. Serial No. 113,228.

To all whom it may concern:

Be it known that we, THOMAS H. LINDLEY and HERMAN SCHREIER, both citizens of the United States, and residents, respectively, of 5 Cedar Rapids, in the county of Linn and State of Iowa, and of Sheboygan, in the county of Sheboygan and State of Wisconsin, have invented certain new and useful Improvements in Rotary Engines; and we 10 do hereby declare that the following is a full, clear, and exact description thereof.

The present invention relates to new and useful improvements in rotary engines, more particularly of that type embodied in 15 Patent No. 986,636 granted to us March 14, 1911 and comprising a cylindrical casing divided by a transverse partition into a pair of compartments in each of which is rotatably mounted a piston block, said blocks 20 forming annular chambers in conjunction with the casing and partition and carrying piston blocks which project across the chambers and coact with gates carried by the casing and also projecting across the chambers whereby steam or other motive fluid introduced between each piston blade and its 25 corresponding gate will impart rotation to the corresponding piston block, these gates being movable out of the chamber to permit successive movements of the piston blades 30 therewith.

It is in general the object of the present invention to simplify and otherwise improve the structure and to increase the efficiency of engines of this character.

More specifically with respect to the supply of steam or other motive fluid to the engine it is an object to provide a means for varying the amount of motive fluid supplied 40 in successive actuations of the engine, whereby to vary the operation thereof.

It is further an object in connection with the gates to provide a means operable immediately prior to movement of the gate to 45 retracted position, for relieving the steam pressure in the chamber which exists between each gate and its corresponding piston blade, whereby resistance offered to such movement of the gate is prevented.

A still further object of the invention resides in the provision of an exceedingly simple combined valve for controlling the 50 inlet port of the chambers.

A still further object resides in the provision of an improved means for associating

the piston blades with their corresponding piston block.

A more detailed object resides in the provision of a means for operating the gates wherein a positive control for the movement 60 thereof is had to prevent "knocking."

With the above and other objects and advantages in view the invention resides more particularly in the novel combination, arrangement and formation of parts herein- 65 after described and pointed out in the appended claims.

In the drawings:

Figure 1 is a side elevation of the improved engine showing more particularly 70 the independent means controlling the movement of the gates and the introduction of motive fluid.

Fig. 2 is a vertical sectional view through the engine as indicated by the line 2—2 of 75 Fig. 3.

Fig. 3 is a horizontal sectional view through the engine as indicated by the line 3—3 of Fig. 2.

Fig. 4 is a horizontal sectional view on the line 4—4 of Fig. 2 through the combined valve.

Fig. 5 is a detailed sectional view on the line 5—5 of Fig. 3 showing adjusting means of the valve cam.

Referring now more particularly to the accompanying drawings, the engine comprises a main casing formed of the substantially circular side walls 5, the annular wall sections 6 and being provided with a transverse partition 7 dividing the casing into a pair of compartments, the side walls 5 having outwardly projected bearing sleeves 8 formed thereon and in which is journaled the engine shaft 9. Fixed on the engine shaft within each compartment is a cylindrical piston block 10 which is of lesser diameter than the casing to form therewith an annular steam chamber. Inasmuch as each piston block and its associated structure is identical in nature, only one will be specifically described and the numerals applied thereto are applied equally to the other.

At diametrically opposed peripheral portions each piston block is provided with a substantially radial slot 11 open at the sides and periphery of the block and seated in this slot is a piston blade 12 which projects outwardly therefrom to extend across 110

the chamber and which is provided with packing members 13 engaging against the sides of the compartment and with a transverse packing member 13^a engaging the outer 5 periphery of the steam chamber. This piston blade is secured in the slot by a tongue 14 at one side thereof which extends into and is secured in a longitudinal open slot 15 in the periphery of the piston block, it being 10 noted for further reference that this slot extends from the piston blade, and that the tongue is spaced inwardly of the mouth of the outer portion of the slot. At diametrically opposed portions the steam chamber is 15 provided with an extension 16 into the peripheral wall of the casing and pivoted at one end of each extension is a gate 17 which is adapted to swing across the chamber to close it, and which when swung into 20 the recess provides clearance for the piston blades. To prevent binding action of the gates on the periphery of the piston block when steam is introduced between the gates and piston blades, and also to provide a tight 25 packing between the ends of the gates and the walls of the compartment, the ends of the gates are extended into sector shaped recesses 18 in the corresponding side and partition wall and the inner edges of these recesses form seating shoulders for the gates. 30 It is noted that the gates extend in opposite directions from the pivotal connections, and are diagonally disposed in operative position across the steam chamber. Communicating with each gate receiving recess, an inlet port 19 is formed in the casing and at the opposite sides of the gates outlet ports 20 are provided in the casing.

Steam is admitted simultaneously through 40 both inlet ports 19, and by the foregoing arrangement an opposed action of the steam on the piston block is procured which prevents the binding strain exerted on the shaft 9 such as would occur were steam introduced 45 at only one side of the casing, as in our said previous patent.

While we have described only two piston blades and their associated mechanisms on the piston block, it is obvious that any number 50 of blades could be employed in suitably spaced relation on the block, the essential feature being the introduction of motive fluid simultaneously into a plurality of portions of the chamber to counter-balance lateral strain on the piston block.

For operating the gates independently of the piston block and blades, a gear wheel 20 is fixed on a cam hub 21, hereinafter to be described, which is in turn fixed on the engine shaft 9 and this gear wheel meshes with 60 a pinion 22 on a shaft 23 which carries also a pinion 24 meshing with a pinion 25 on a horizontal shaft 26 and this shaft 26 drives a pair of cam shafts 27 through the medium 65 of intermeshing beveled gears 28. A pivot

shaft 29 of each gate 17 is extended outwardly of the casing and carries a lateral arm 30 with which is connected a cam rod 31 slidably mounted in bearings 32 on the side of the casing and this cam rod comprises sections held in laterally offset relation by a cam plate 33 which is engageable by cam wings 34 on the cam shaft 27, the lower section of the cam rod extending between said wings and extended into a dash 75 pot 35 which opposes movement of the cam rod in procuring retracting movement of the gate, it being noted that retracting movement of each cam rod is effected by the cam wings. For retaining the gate in operative 80 position across the chamber, a spring 36 is mounted on each rod. Thus the dash pot opposes the movement of the spring, and the spring opposes the movement of the cam to procure a positively controlled operation of the gates to prevent excessive movement thereof, commonly termed "pounding."

The foregoing mechanism is so timed as to procure retracting movement of the gates immediately prior to movement of the piston blades therewith and to procure advancing movement of the gates immediately subsequent to movement of the blades therewith.

Although in the limit of movement of the piston blades away from the gates, the pressure of motive fluid would be considerably reduced due to its expansion, yet a considerable resistance would still be offered to retracting movement of the gates in view of the atmospheric pressure in those portions 95 of the chamber rearwardly of the gates. To relieve this pressure and thus permit ready 100 retracting actuation of the gates, we utilize the particular arrangement of the piston block slot 15 in advance of the blades with 105 respect to their direction of movement utilized as a by-pass channel. It is realized that any suitable by-pass means preferably carried by the piston could be utilized. Thus as each piston blade moves toward the 110 corresponding gate, the slot 15 will extend past the gate to procure a balancing of pressure at both sides thereof.

Taking up now the combined valve means for introducing motive fluid to the different steam chambers, a valve casing 37 is mounted transversely on the casing and is provided with a central inlet port into which extends the main supply pipe 38. At each side of the central inlet port the casing is 115 provided with a pair of opposed outlet ports 39 which are connected by pipes 40 with the inlet ports of one of the steam chambers. For independently controlling each pair of ports 39 to provide for simultaneous opening thereof, a pair of hollow valve heads 41 are rotatably mounted in the end portions 125 of the valve casing and provided with openings 42 adapted to align with the corresponding valve outlet ports 39, these hollow 130

heads being open at their inner ends and having at their outer ends, stems 43 extending through and journaled in the ends of the valve casing, it being noted that these stems 5 extend outwardly of the sides of the main engine casing. For actuating each of the valve heads 41, a cam rod 44 is slidably mounted in a bearing bracket 45 on the corresponding side of the main engine casing 10 and is loosely connected at one end to a lateral arm 46 on the end of the valve stem. Fixed on this rod is a sleeve 47 which is connected by a link 48 with one end of a lever 49 which is pivoted to the casing at its other 15 end and which carries an intermediate roller 50 engageable by a cam projection 51 on the corresponding cam hub 21 heretofore mentioned. The rod 44 is normally urged to a position closing the valve outlet ports 39 by 20 a spring 52 mounted thereon and bearing against the collar 47 and the bracket 45.

The cam 51 is timed to open the corresponding valve ports 39 immediately subsequent to advancing movement of the cams 25 of the corresponding steam chamber, and the cam projection 51 holds the valve open during a portion of the rotation of the piston blades between the gates. The valve ports are then closed and the blades travel 30 the remainder of the distance between the gates by expansion of the steam introduced into the chamber. It is under differing conditions desired to vary the amount of steam introduced into the chamber upon successive 35 operations of the valve, and to accomplish this, a means is provided for varying the length of the operative face of the cam projection 51, which comprises a plate 53 loosely mounted on the engine shaft between 40 the cam hub and the casing and provided in its inner face with an annular recess 54 concentric with the shaft and having slidably mounted therein blocks 55 from which extend bolts 56 passed through slots 57 in 45 the plate and passed through the cam hub and adapted to clampingly hold the plate to the cam hub, said plate being provided with cam projections 58 which upon rotative adjustment of the plate are extensible 50 past the cam portions 51 of the cam hub to thus vary the total length of operative cam face.

Pipes 59 extend from adjacent exhaust ports 20 of the steam chambers to a common exhaust head 60 at each side of the casing and from these exhaust heads, communicating pipes 61 extend. The main supply pipe 38 is provided with a valve 62 and immediately above this valve a bleed pipe 63 55 communicates with the main supply pipe and extends to one of the exhaust pipes 61, whereby when the engine is not running, water of condensation of steam in the main supply pipe will be conveyed away without 60 passing through the engine, this bleed pipe 65

being controlled by a valve 64 adjacent its juncture with the main supply pipe. Associated with the main supply pipe above and below the valve 62 respectively is an oil inlet 65 connected with a suitable oil supply 70 mechanism 66, and a conventional steam gage 67, although it will be appreciated that these devices are not particularly pertinent to the present invention.

We claim:

1. In a rotary engine, the combination with a cylindrical casing, a piston block rotatable in said casing to define therewith an annular chamber, a shaft operable by the piston block, a piston blade carried by the 80 piston block and projecting across the chamber and a gate movable across the chamber, of a slidable cam rod connected with the gate for advancing and retracting said gate, a spring connected with the rod for urging 85 it in one direction of movement, a dash pot connected with the rod and operable in opposition to the spring, and a cam member operable by the said piston block shaft and engageable with the cam rod in opposition 90 to the spring.

2. In a rotary engine, the combination with a cylindrical casing, a piston block rotatable in said casing to define therewith an annular chamber, a piston blade carried by 95 the piston block and projecting across the chamber, a gate movable across the chamber, an inlet port for the chamber and a valve controlling said inlet port; of means for advancing and retracting the gate in the chamber said inlet port valve being normally closed and means for opening said valve subsequent to advancing movement of the gate for a predetermined period of time, said means being adjustable to vary the lengths 100 of the periods of time which the valve is open.

3. In a rotary engine, the combination with a cylindrical casing, a piston block rotatable in said casing to define therewith an 110 annular chamber, a piston blade carried by the piston block and projecting across the chamber, a gate movable across the chamber, an inlet port for the chamber and a valve controlling said inlet port; of means for advancing and retracting the gate in the chamber and means urging said valve to closing position, a shaft operable by the piston block, a cam on said shaft, a member connected with the valve and engageable by the 120 cam for opening the valve and means for varying the length of the operative face portion of the cam.

4. In a rotary engine, the combination with a cylindrical casing, a piston block rotatable in said casing to define therewith an annular chamber, a piston blade carried by the piston block and projecting across the chamber, a gate movable across the chamber, an inlet port for the chamber and a 130

valve controlling said inlet port; of means for advancing and retracting the gate in the chamber and means urging said valve to closing position, a shaft operable by the piston block, a cam comprising a section fixed on the shaft and a section rotatively adjustable with respect to the first section, a face portion of the second section forming an extension of the face portion of the first section and a member engageable by the said face portions of the cam sections for opening the valve.

5. In a rotary engine, the combination with a cylindrical casing, and a piston block 15 rotatable in said casing to define therewith an annular chamber; said piston block being provided in its peripheral portion with a transverse slot open at its sides and periphery and further provided with an open 20 longitudinal peripheral slot communicating with the first slot, a piston blade in the transverse slot projecting from the periphery of the block and a securing tongue on said blade projecting into the longitudinal slot.

6. In a rotary engine, the combination with a cylindrical casing, and a piston block rotatable in said casing to define therewith an annular chamber; said piston block being provided in its peripheral portion with a transverse slot open at its sides and periphery and further provided with a longitudinal 30 peripheral slot communicating with the first slot, a piston blade in the transverse slot 35 projecting from the periphery of the block, a securing tongue on said blade projecting

into the longitudinal slot, a gate movable across the annular chamber, means for advancing and retracting said gate in the chamber, and said longitudinal slot of the 40 piston block forming a by-pass to relieve pressure in the chamber immediately prior to retracting movement of the gate.

7. In a rotary engine the combination with a cylindrical casing, a journaled shaft 45 in the casing, a partition in the casing, piston blocks on the shaft at the sides of the partition and forming a pair of annular chambers in the casing, a pair of piston blades on each block extending across the 50 corresponding chamber, a pair of gates movable across each chamber, and a pair of inlet ports in the casing for each chamber, of a cylindrical valve casing having a central inlet port and a pair of spaced outlet ports at 55 each side of the central inlet ports having communication with the inlet ports of the annular chambers, hollow valve heads rotatably mounted in the valve casing at the sides of the central inlet port, ports in the 60 valve heads adapted for registry with corresponding outlet ports of the valve casing and means for independently operating the valve heads.

In testimony that we claim the foregoing 65 we have hereunto set out hands at, respectively, Cedar Rapids, in the county of Linn and State of Iowa, and Milwaukee, in the county of Milwaukee and State of Wisconsin.

THOMAS H. LINDLEY.
HERMAN SCHREIER.
